INVENTOR
UNITED STATES PATENT OFFICE.

RUDOLPH M. HUNTER, OF PHILADELPHIA, PENNSYLVANIA, ASSIGNOR TO H. W. BUTTERWORTH & SONS COMPANY, A CORPORATION OF PENNSYLVANIA.

APPARATUS FOR FEEDING AND GUIDING CLOTH.

1,389,826.

Specification of Letters Patent. Patented May 11, 1920.

Application filed May 5, 1915. Serial No. 25,894.

To all whom it may concern:

Be it known that I, RUDOLPH M. HUNTER, a citizen of the United States, and resident of Philadelphia, county of Philadelphia, 5 and State of Pennsylvania, have invented an Improvement in Apparatus for Feeding and Guiding Cloth, of which the following is a specification.

The object of my invention is to provide 10 a suitable means for feeding cloth to tentering and other textile machines, more especially of the character of what is known in the art as a "feeder and guider." In machines of this class, the cloth is maintained 15 taut transversely of its length and guided while in such condition into the cloth clamps by which it is subsequently conveyed and stretched. More particularly, my object is to provide means for operating the guide 20 rolls relatively, to or from each other, comprising a motor operated by the combined action of a fluid and compressed air or gas, said means being controlled by the fabric as it passes between the rolls.

25 My invention consists of means for controlling the feeding of the cloth when operated by a liquid actuated motor device, said motor device in turn rendered active by compressed air or gas admitted to and 30 exhausted from the motor under the control of a valve, itself controlled by the fabric which is being guided through the machine, all of which is fully set out hereinafter and more particularly pointed out 35 in the claims.

My invention also comprehends details of construction which, together with the features above specified, will be better understood by reference to the drawings, in 40 which:—

Figure 1 is a side elevation of my improved feeder and guider with a portion in section; Fig. 2 is a front elevation; and Fig. 3 is a sectional view of the valve devices of the motor taken on line $x-x$ of Fig. 1.

Ordinarily there are one or more pairs of 50 guide rolls for feeding and guiding the selvages of the woven fabric to the cloth clamps of the tentering machine, but it will suffice to describe a single one of the devices.

2 is a frame adjustably clamped in position upon the main frame of the machine.

This frame 2 is provided with a guide plate 55 3 over which the cloth is guided, said plate having an opening through which the adjustable roll 4 operates. 5 is a roll arranged above the opening in the plate and is suitably journaled upon the frame 2. The roll 60 4 is journaled in a pivoted frame 6, hinged to the frame 2 at 7 and having an operating arm 8. This frame 6 is in general structure a bell-crank lever. The free end of the arm 8 extends downward and rests upon the 65 center disk 13 of the diaphragm 11, said diaphragm being clamped at 12 in the open top of the motor body 9. The weight of the roll 4 and frame 6 presses the arm 8 downward and the thrust upon the diaphragm is 70 transferred to the stop 14 in the motor below the disk 13 of the diaphragm. The body 9 forms a reservoir for a fluid, preferably oil, and this fluid acts to raise the diaphragm 75 at its center to operate the bell-crank lever frame 6^a and the roll 4. This body part 9 is adjustably clamped at 15 to the main frame 2 so that it may be adjusted vertically to accurately position the roll 4 with respect to the roll 5. One end of the body 9 is 80 provided with a chamber 17 rising to a level above the diaphragm, and this chamber may be provided with a sealed inlet 16 through which the oil may be introduced. When the oil reservoir is properly filled, the 85 level of the oil will extend nearly to the top of the chamber 17. The body is further provided with a lateral arm 18 having a vertical aperture in its end and a horizontal hole or conduit 24 opening into the 90 upper part of the air chamber 17 above the oil. The control valve device 19 has at its upper part a neck 21 which fits tightly into the hole on the end of the arm 18 and the valve device is clamped in position by the 95 nut 22. The neck portion and upper part of the valve device are provided with a port 23 which communicates with the port or conduit 24 of the arm 18. Within the body of the valve device 19 is a valve piece 100 20 which is pivoted to rock. The upper end of this valve piece snugly fits the curved wall 19^a of the valve casing, and is provided with an air supply port 20^a and an exhaust channel 20^b. The interior of the rocking 105 valve is made hollow as at 20^b and is in communication with the compressed air supply pipe 25. The valve piece is journaled

in the casing in any suitable manner, and has an axial extension 27 which is secured to a bell-crank arm 30 having a counter-weight 31 which normally causes the valve 5 piece to rock into position in which the ports 20^a and 23 come into alignment to admit compressed air through the port 24 into the air chamber 17, and thereby apply pressure upon the top of the oil to cause the 10 same to exert a pressure against the under side of the diaphragm 11 and thereby lift the roll 4 toward the roll 5 for gripping the traveling fabric between them. When the valve piece 20 is moved in the opposite 15 direction, the exhausting position is assumed as indicated by Fig. 3, in which case the exhaust channel 20^c comes into alignment with the port 23 and allows the compressed air from the chamber 17 to expand 20 outwardly into the casing of the valve device. This action allows the oil to rise in the chamber 17 with a consequent lowering of the center of the diaphragm 11 and similarly a lowering of the roll 4, this position 25 being indicated in Fig. 1. The oscillation of the valve piece 20 to perform this function is accomplished by the pivoted feeler finger 28 which is pivoted at 29 to the frame 2, and moreover has its upper end 30 extending through the guide plate 3 to be acted upon by the selvage of the fabric passing between the rolls 4 and 5, and having its lower end arranged to act upon the arm 30 attached to the axial extension 27 of the 35 valve piece.

Ordinarily the rolls 4 and 5 are set at a slight angle to the line of travel of the fabric so that when the fabric is pinched between the rolls, while being drawn between them, the tendency will be to stretch the fabric transversely. This action takes place normally by the action of the rolls 4 and 5 under the influence of the compressed air. Whenever the selvage of the 40 fabric strikes the feeler finger 28, it oscillates the latter and throws the valve piece 20 into the exhausting position (Fig. 3). The air pressure then being cut off to the motor device and the pressure therein relieved, the roll 4 drops sufficiently to relieve the bite upon the fabric which tends to contract laterally. These actions take 45 place automatically so that the width of the fabric remains approximately the same.

The particular device shown may be materially varied in construction, and I do not restrict myself to any particular character of valve, but have shown a type of valve which has been found well adapted to the 50 purpose of this invention. The general construction may be more or less varied without departing from the spirit of the invention, and I therefore do not restrict myself to the minor details.

Having now described my invention, what

I claim as new and desire to secure by Letters Patent, is:—

1. In an apparatus for feeding and guiding cloth to tentering and other machines, a pair of rolls between which the cloth adjacent to its selvage is caused to pass and one of which rolls is mounted with capacity to be moved to or from the other, in combination with a fluid pressure means for automatically moving the movable roll comprising a liquid containing chamber, a diaphragm forming a wall of said chamber and acted upon by the liquid therein, said diaphragm arranged to operate the movable roll, a valve device for admitting compressed air or gas to the liquid containing chamber above the liquid therein and permitting the exhaust of said air or gas therefrom, and a freely movable sensitive finger arranged to be actuated by the cloth, whereby the valve 70 is operated for controlling the admission and exhaustion of the compressed air or gas to and from the liquid containing chamber for causing the diaphragm to be moved and whereby the movable roller is actuated. 75

2. In an apparatus for feeding and guiding cloth to tentering and other machines, a pair of rolls between which the cloth adjacent to its selvage is caused to pass, one of said rolls mounted in a hinged frame, 90 combined with a chamber having a flexible diaphragm wall arranged to act upon the hinged frame, the said chamber filled with liquid above the level of the diaphragm and providing an air or gas chamber in its upper part, a source of compressed air or gas, and valve devices controlled by the cloth passing between the rolls for regulating the admission of compressed air or gas to and the exhaust from the air or gas space above 95 the liquid containing chamber, whereby the liquid is caused to operate the diaphragm and thereby actuate the hinged frame and the roll carried thereby. 100

3. In an apparatus for feeding and guiding cloth to tentering and other machines, a pair of rolls between which the cloth passes, said rolls mounted to permit relative movement with respect to each other, combined with a liquid container having a flexible diaphragm wall arranged to impart relative movement to the rolls, said container having an upper chambered part into which the liquid extends above the level of the diaphragm wall and also to provide a 115 gas or air space above the liquid, said container also provided with a laterally projecting arm containing an air or gas conduit opening from said space, and a valve device arranged to be actuated by the fabric 120 for controlling the admission and escape of compressed air or gas through the conduit said valve device having a neck portion extending through and clamped in position 125 upon the arm and providing a port in alignment 130

ment with the conduit whereby said valve device is supported by the container.

4. In apparatus for feeding and guiding cloth to tentering and other machines, a pair of rolls between which the cloth passes, one of said rolls mounted for movement to and from the other, a liquid container having a flexible diaphragm wall arranged to operate the movable roll, said container having an upper chambered part into which the liquid extends above the level of the diaphragm wall and also to provide a gas or air space above the liquid, said container also provided with a laterally projecting arm containing an air or gas conduit opening from said space, a valve device for controlling the admission and escape of compressed air or gas through the conduit comprising a case having a neck portion extending through and clamped in position upon the arm and providing a port in alignment with the conduit whereby said valve device is supported by the container, a movable valve piece ar-

ranged within the case and adapted to control the port thereof, and means controlled by the cloth passing between the rolls for operating the said valve piece.

5. In an apparatus for feeding and guiding cloth to tentering and other machines, a pair of rolls, one of which is mounted to be reciprocated to and from the other, combined with a liquid operated motor for reciprocating the movable roller, a source of air or gas pressure, valve devices for admitting air or gas pressure to and from the liquid operated motor and above the liquid thereof, and controlling means arranged to be actuated by the cloth for operating said valve devices.

In testimony of which invention I here- 40 unto set my hand.

R. M. HUNTER.
